SECRECY INTERCOMMUNICATING TELEPHONE SYSTEM

William H. Waite, Lynbrook, N. Y., assignor to
Dictograph Products Company, Inc., New
York, N. Y., a corporation of Delaware

Application January 13, 1938, Serial No. 184,779

10 Claims. (Cl. 179—39)

This invention relates to an intercommunicating telephone system in which complete secrecy of conversation is maintained between any two communicating stations.

- 5 A conventional intercommunicating telephone system comprises a number of stations, each connected to its own pair of talking wires, and each equipped with a plurality of keys or switchees by means of which the telephone receiver and transmitter at any station can be connected to the pair of talking wires corresponding to any other station. Additional common wires are required to supply voltage from the talking and signalling batteries to their respective circuits. In the majority of such systems, no provision is made for 10 secrecy of communication between any two stations, so that it is possible for a third station to be connected to one of two communicating stations. Other systems which provide for secrecy 15 of communication are not positive in their action, as in the case where the connection between two stations is contingent upon the ability of the calling station to operate the buzzer or audible signal at the called station.
- 20 25 In accordance with this invention a secrecy intercommunicating telephone system is provided which utilizes a control relay connected in parallel with the pair of talking wires of the called station, which operates in one of two ways, depending on the condition of the talking wires. If the called line is not in use, the second station can be signalled and the talking circuit closed. If the called line is busy, however, an audible signal operates at the calling station, notifying the operator at that station of the 30 condition of the line, and at the same time making it impossible for him to close the talking circuit to the busy station.

Also, energization of the talking circuit to any 35 substation energizes the audible signal at that station, provided that the switch at that station is closed, or, alternatively, if the telephone receiver thereof is on its hook.

In the preferred embodiment of this invention, 40 the operator at one station desiring to call a second station removes his receiver from its hook and manipulates the key corresponding to the desired station. This connects the control relay, directly across the pair of wires of the called line. If the line is not in use, this control relay is 45 not energized, and in this position it completes a circuit to a second relay, hereinafter called the line relay, through a ringing key. The operation of the ringing key applies part of the voltage of the talking battery to this line relay,

thereby closing its contacts. The line relay is equipped with a mechanical latch so that once it has been energized, its contacts will remain closed until the latch is released by the replacement of the receiver at the calling station on its hook, or by the manipulation of another calling key at the calling station. The operation of the line relay connects the telephone instrument of the calling station to the pair of talking wires corresponding to the called station, thus connecting these wires to the talking battery, and energizing a relay at the called station. This last relay completes a circuit through the audible signal and the signalling battery, its sound indicating that the station is being called. The operator thereupon removes his receiver from its hook and the conversation may begin.

In the case where the called line is initially busy, the control relay is energized the instant that the key is operated at the calling station. When the ringing key is then actuated, a circuit is completed, energizing a signal or buzzer relay at the calling station, and the sound of the buzzer indicates to the caller that the called line is busy. The control relay remains closed as long as the called line is busy, and in this position it is impossible for the line relay to operate and connect the calling station telephone instrument to the busy line.

It will be seen that the new system of this invention provides the advantages of simplicity of previous systems, and in addition provides for absolute secrecy of interstation conversations without complicating operations or apparatus.

For a more complete understanding of the invention, reference may be had to the accompanying drawings, in which:

Figure 1 is a schematic diagram illustrating an embodiment of the invention;

Fig. 2 is a simplified diagram of the elementary telephone circuit upon which this invention is based; and

Fig. 3 illustrates a mechanical arrangement for holding the line relay closed after it has once been energized.

While the system can be adapted to include any number of stations, only two stations, A and B, are shown in Fig. 1, since their method of operation is identical with that of any other two stations of the system.

Each station comprises the usual receiver 10 and a microphone or transmitter 11, a switch 12 actuated by the receiver hook 13, a key or switch 14 corresponding to each of the other stations 55

in the system, a control relay 15, a line relay 16, and a signal relay 17.

The key or switch 14 consists of four contact springs, of which the first spring 18 is normally disengaged from the second spring 19, and the third spring 20 is normally disengaged from the fourth spring 21. An insulating bar 22 between the springs 19 and 21 causes them to move as a unit.

10 Considering station A, the first spring 18 is connected by wire 23 to common talking wire 24, and third spring 20 is connected by wire 25 to the second common talking wire 26. Second spring 19 is connected by wire 26' to a spring 15 contact 27 on the line relay 16, and by wire 54 through control relay 15 and wires 55 and 28 to fourth spring 21 of key 14, which is also connected to contact 29 of line relay 16.

20 Normally disengaged from relay contact 27 is contact spring 30, mechanically connected to but insulated from the armature 31 of line relay 16. The armature 31 is also mechanically connected to but insulated from contact spring 33, which normally engages a spring contact 34. Between 25 the spring 33 and a spring 35 is an insulating block 36 adapted to move spring 35 into engagement with contact 29 as the relay 16 is energized. Control relay 15 armature 56 normally engages contact 57 connected by wire 63 through line 30 relay 16 and wires 64 and 41 to negative common wire 42.

25 Contact spring 33 of line relay 16 is connected by wire 79 to contact 78, which is normally disengaged from armature 56 of control relay 15, the armature 56 being connected by wire 62 through normally open ringing key 58 and wires 59 and 47 to common positive wire 48.

30 Receiver switch 12 comprises three spring contacts and the receiver hook 13. The first spring 40 37 is part of the talking circuit, and is connected through resistor 38, receiver 10 and the microphone or transmitter 11, wire 39, impedance coil 40, and a wire 41 to the negative line wire 42, which is connected to the negative terminal of 45 the talking battery 43.

35 The second spring 44 of switch 12 is connected through wire 45, impedance coil 46, and wire 47 to the positive line wire 48, which is connected to the positive terminal of the talking battery 43.

40 The receiver hook 13 of the switch 12 is connected through wire 49 to talking wire 50 of station A and by wires 49 and 51 to the spring 35 on the line relay 16.

45 At station B the receiver hook 13 is connected by wire 52 to the talking wire 26, and, as before, wire 51 connects the wire 52 with the spring 35 of the line relay 16.

50 The lower contact of receiver switch 12 normally engages hook 13 and is connected to contact 34 of line relay 16 and by wire 67 through signal relay 17, and wires 68 and 41 to common negative signal wire 42. The armature 69 of signal relay 17 is connected by wire 75 to common negative signal wire 74 and, when actuated, 55 engages contact 70 to complete the local signal circuit through buzzer 71 and impedance 72 to common positive signal wire 73.

55 In operation, when the party at station A desires to communicate with station B, he removes his receiver 10 from its hook 13, thus causing hook 13 to disengage contact 65 and engage contact 44, which is caused to engage contact 37. He then manipulates the key switch 14 corresponding to station B to engage contacts 18, 70 19, and 20, 21. This completes a circuit from

common wire 24, wire 23, contacts 18 and 19, wire 54, the control relay 15, wire 55, contacts 21 and 20, wire 25 and common talking wire 26. If station B is not busy, there is no voltage across the wires 24 and 26, and control relay 15 will not be energized and its armature 56 will remain engaged with contact 57. Actuation of the ringing key 58 closes a circuit from common positive line 48 of the talking battery 43, wires 47 and 59, closed contacts 60 and 61 of the ringing key 58, 10 wire 62, armature 56 of the control relay 15 engaging contact 57, wire 63, line relay 16 and wires 64 and 41 to common negative wire 42 of the talking battery 43. The armature 31 of energized line relay 16 is maintained in the raised position by a mechanical latch, which will be described later.

15 The closed contacts of energized line relay 16 complete a signalling circuit between station A and station B traceable at station A from common positive line 48, wire 47, impedance coil 46, wire 45, contact 44 engaging the receiver hook 13, wires 49 and 51, closed line relay contacts 35 and 29, wire 28, closed key 14, contacts 21 and 20, wire 25, common talking wire 26 to station B, 20 wire 52, receiver hook 13 engaging contact 65, wire 67, signal relay 17 and wires 68 and 41 to common negative line 42. This completes the station B signal circuit from common negative wire 14 of the signalling battery 76, wire 75, armature, 25 69 of signal relay 17 engaging the spring contact 70, buzzer 71, protective resistor 72, to common positive line 73 of the signalling battery 76. The buzzer indicates to the party at station B that he is being called and the buzzer signal is maintained until the receiver 10 is removed from the hook 13 of station B, when the buzzer circuit is broken by the disengagement of the spring contact 65 with the receiver hook 13.

30 The removal of the receiver from its hook at 40 station B releases the receiver hook 13 to cause engagement of contacts 44 and 37, thus completing the talking circuit between the two stations, which is traceable at station A from common talking wire 24, wire 23, contacts 18 and 19 of 45 key 14, wire 26', contacts 27 and 30 of the line relay 16, wire 39, station A microphone or transmitter 11, receiver 10, protective resistor 38, contact 37, contact 44 engaging the receiver hook 13, wires 49 and 51, contacts 29 and 35 of the line 50 relay 16, wire 28, contacts 21 and 20 of the key 14 and wire 25 to common talking wire 26. From common talking wire 26 the talking circuit is traced to wire 52 at station B, receiver hook 13 engaging contact 44, contact 37, protective resistor 38, receiver 10, microphone or transmitter 11, wires 39 and 77 back to common talking wire 24.

55 The positive terminal of the talking battery 43 is connected to the talking circuit at both stations A and station B through common positive line wire 48, wire 47, impedance coil 46, wire 45 and the engaged receiver switch 12 contacts 37 and 44. The negative terminal of the talking battery 43 is also connected to the talking circuit at both stations through common negative line 65 42, wire 41, impedance coil 40 and wire 39 to the microphone or transmitter 11.

60 Fig. 2 is a simplified diagram of the talking circuit. The impedance coils 40 and 46 do not 70 retard direct current to the talking circuit, but prevent the passage of voice currents through the talking battery 43. The impedance of the talking circuit is made low with respect to that of the impedance coils 40 and 46 to insure that 75

most of the voice current will circulate between the telephone instruments of the stations and little or none will pass through the common talking battery 43. This tends to reduce the possibility of cross talk where a number of conversations take place between different stations simultaneously, and thus helps to maintain complete secrecy of communication.

In the case where station B is initially busy, 10 the voltage of the talking battery 43 is impressed across the lines 24 and 26 so that the control relay 15 is energized the instant that the key 14 is manipulated. Its armature 56 engages the contact 78, thus closing a circuit through the 15 ringing key 58. When this key 58 is actuated, the voltage of the talking battery 43 is applied through common negative wire 48, wires 41 and 59, the engaged contacts 60 and 61 of the ringing key 58, wire 62, armature 56 of the control relay 20 15 engaging contact 78, wire 79, normally engaged contacts 33 and 34 of the line relay 16, wire 67, signal relay 17 and wires 68 and 41 to common positive line 42. The armature 69 of signal relay 17 engages contact 70, thus energizing 25 the local buzzer 71. The buzzer signal accordingly is an indication to the calling party at station A that station B is busy. It should be observed that as long as station B is busy, it is impossible to energize the line relay 16 30 and thus connect the telephone instruments at station A to the talking wires corresponding to station B, whereby absolute secrecy is maintained.

The mechanical latch for holding the armature 31 of the line relay 16 in the raised position is illustrated in Fig. 3 and may be an adaptation of the latch disclosed in Koch Patent No. 2,003,-689. The receiver hook 13 is illustrated as of the cradle type for receiving combined receiver 40 and transmitter handset. The weight of the handset on the receiver hook 13 is transmitted by rod 80 to a bell crank 81, 83, which is pivoted at 82. The end 84 of arm 83 engages arm 85 on the locking bar 86 having a bell crank 87 pivoted at 88 and connected to the end of a thrust rod 89, which is slotted to receive a fixed pin 90, and bears on a latch 91 pivoted at 92 and held in contact with the thrust rod 89 by light tension spring 93 connected at opposite 50 ends 94 and 95 to the respective thrust rod 89 and latch 91.

When the handset is removed from the hook or cradle 13, the usual spring, not shown, raises 13 until arm 81 engages the stop 96 to disengage 55 the end 84 of arm 83 from arm 85 so that its end 86 drops in position for engagement in one of the notches 99 when pivoted switch key 14 is manipulated. The thrust rod 89 is thus raised slightly, so that when the line relay 16 is energized, its armature 31 engages the notch 101 and is locked in this position by the latch 91.

The latch 91 is released either by replacing the handset on the receiver hook or cradle 13, or by manipulating one of the keys 14. In the 65 former case, thrust rod 89 drops, disengaging latch 91 from the armature 31 to release it. In the latter case, the manipulation of a key 14 raises the locking bar 86, thus releasing the latch 91 in the same way.

70 Although a preferred embodiment of the invention has been illustrated and described herein, it is to be understood that the invention is not limited thereby, but is susceptible to changes in form and detail within the scope of the appended claims.

I claim:

1. In a telephone system, the combination of a plurality of stations each having a telephone instrument, talking lines interconnecting said instruments, a switch at each station for energizing the talking line of a selected other station, a control relay across said talking line at each local station responsive to previous energization of a talking line by a remote station switch upon actuation of the corresponding local 10 switch calling said last-named remote station, and a connection to the said last-named local station telephone instrument controlled by said relay whereby communication between said last-named local station telephone instrument and 15 said last-named remote station telephone instrument is prevented while the latter remains busy.

2. In a telephone system, the combination of a plurality of stations, each having a telephone instrument, talking lines interconnecting said instruments, a switch at each station for energizing the talking line of a selected other station, a control relay across said talking line at each local station responsive to previous energization 20 of a talking line by a remote station switch upon actuation of the corresponding local switch calling said last-named remote station, connections to the said last-named local station telephone instrument controlled by said relay whereby communication between said last-named local station telephone instrument and said last-named remote station telephone instrument is prevented while the latter remains busy, and a signal at 25 said last-named local station controlled by said relay for indicating that the called last-named 30 remote station is busy.

3. In a telephone system, the combination of a plurality of stations, each having a telephone instrument, talking lines interconnecting said instruments, a switch at each station for connecting the corresponding talking line to a remote station instrument, and a control relay at each station across the corresponding talking line responsive to previous energization of the talking line of a selected remote station for 40 disabling the local station telephone instrument 45 while the talking line of the selected remote station remains energized.

4. In a telephone system, the combination of a plurality of stations, each having a telephone instrument, talking lines interconnecting said instruments, a switch at each station for connecting the corresponding talking line to a remote station instrument, a control relay at each station across the corresponding talking line responsive to previous energization of the talking line of a selected remote station for disabling the local station telephone instrument while the talking line of the selected remote station remains energized, and a signal at said last-named local station controlled by said relay for indicating that the selected remote station is busy.

5. In a telephone system, the combination of a plurality of stations each having telephone instruments, talking lines interconnecting said stations, a switch at each station for connecting the corresponding line to a selected remote station, a local control relay at each station across the corresponding talking line, normally closed contacts on said relay preparing a talking circuit to a remote station selected by the corresponding switch, and second contacts on said relay disabling the local station instrument upon actuation of said relay in response to previous energ- 70 75

gization of the selected remote station talking line.

6. In a telephone system, the combination of a plurality of stations each having telephone instruments, talking lines interconnecting said stations, a switch at each station for connecting the corresponding line to a selected remote station, a local control relay at each station across the corresponding talking line, normally closed contacts on said relay preparing a talking circuit to a remote station selected by the corresponding switch, second contacts on said relay disabling the local station instrument upon actuation of said relay in response to previous energization of the selected remote station talking line, and a signal at said local station responsive to energization of said relay for indicating that the selected remote station is busy.

7. In a telephone system, the combination of a plurality of stations each having a telephone instrument, talking lines interconnecting said instruments, a line relay at each station controlling the corresponding talking line to a selected remote station, a switch at each station controlling said relay, and a control relay across said corresponding talking line responsive to previous energization of the remote station instrument selected by said switch for disabling the corresponding line relay while the selected remote station remains busy.

8. In a telephone system, the combination of a plurality of stations each having a telephone instrument, talking lines interconnecting said instruments, a line relay at each station controlling the corresponding talking line to a selected remote station, a switch at each station controlling said relay and a control relay across said corre-

sponding talking line responsive to previous energization of the remote station instrument selected by said switch for disabling the corresponding line relay while the selected remote station remains busy, and a signal at the talking station responsive to energization of said control relay for indicating that the called remote station is busy.

9. In a telephone system, the combination of a plurality of stations each having a telephone instrument, talking lines interconnecting said instruments, a line relay at each station controlling the corresponding talking line to a selected remote station, a switch at each station controlling said relay, a control relay across said corresponding talking line responsive to previous energization of the remote station instrument selected by said switch for disabling the corresponding line relay while the selected remote station remains busy, a signal relay at the calling station responsive to actuation of said control relay, and a signal actuated by said signal relay to indicate that the called station is busy.

10. In a telephone system, the combination of a plurality of stations each having a telephone instrument, talking lines interconnecting said instruments, a line relay at each station, a switch at each station for energizing the corresponding line relay to connect the corresponding local telephone instrument to the talking line of a selected remote station, and a control switch interposed between said first switch and line relay actuated by said control relay to disable said line relay in response to previous energization of the talking line of said selected remote stations.

WILLIAM H. WAITE.
